[57] CLAIM

The ornamental design for a miniature sander, as shown and described.

DESCRIPTION

FIG. 1 is a perspective view;

FIG. 2 is a left side view thereof;

FIG. 3 is a front view;

FIG. 4 is a rear view;

FIG. 5 is a top view; and,

FIG. 6 is a bottom view.

The right side view is the same as a mirror image of the left side view shown in FIG. 2. The broken lines showing the sanding tool are for illustrative purposes only and form no part of the claimed design.

FIG. 1

FIG. 2

FIG. 5

FIG. 6

FIG. 4

FIG. 3
